UNITED STATES PATENT OFFICE.

CHARLES F. GOLDBECK, OF PHILADELPHIA, PENNSYLVANIA.

COIN-WRAPPER.

1,001,138.

Specification of Letters Patent. Patented Aug. 22, 1911.

Application filed February 15, 1911. Serial No. 608,835.

To all whom it may concern:

Be it known that I, CHARLES F. GOLDBECK, a citizen of the United States, residing in the city and county of Philadelphia, State 5 of Pennsylvania, have invented a new and useful Device for Wrapping Coin, of which the following is a specification.

My invention consists of a device for 10 wrapping coin embodying means for holding and guiding the wrapper and supporting the coin in a firm and convenient manner and admitting of the rolling of the wrapper in a similar manner.

It consists further of novel means for 15 suspending the coin in upright position on the wrapper preparatory to rolling of the latter.

It consists further of novel details of construction, as will be set forth and claimed.

For the purpose of explaining my invention, the accompanying drawing illustrates a satisfactory reduction of the same to practice, but the important instrumentalities thereof may be varied, and so it is to be understood that the invention is not limited 25 to the specific arrangement and organization shown and described.

Figure 1 represents a perspective view of 30 a coin wrapping device embodying my invention. Fig. 2 represents a longitudinal vertical section of a portion thereof on an enlarged scale. Fig. 3 represents a transverse vertical section of a portion thereof on an enlarged scale.

Similar letters of reference indicate 35 responding parts in the figures.

Referring to the drawings:—A designates the base of the device, the same being somewhat of the form of a box provided with drawers B in which may be contained respectively 40 an ink pad, a rubber stamp, a bottle of mucilage, a brush, and a bottle of stamping ink. On the top of said base are downwardly curved beds C which extend transversely on the base and are secured to the front and rear walls thereof. In each 45 of said beds are transversely-extending openings D through which protrude portions of transversely extending rollers E which are mounted on the base A, and in a measure form a portion of the bed, it being noticed that the beds and rollers are of different diameters for the purpose of wrapping coins of varying denominations. Pivotaly mounted on the elevated portions 50 or peaks F of the beds are bars or rods G, which may be lifted to admit a coin-wrap-

per thereunder and then lowered so as to rest on the wrapper, which latter has an end portion placed on one of the peaks, the bar then acting as a sufficient weight to 60 prevent rising and accidental displacement of the wrapper. Rising from the ends of the peaks opposite to the pivots or hinges of the bars are bifurcations H, each of which form keepers to receive the adjacent end 65 of a bar, and so prevent shifting of the latter when in operative position especially in the direction of the motion of the wrapper as the latter is drawn thereunder.

Connected with the base in front of the 70 beds C is the bracket J, which is projected outwardly from the wall of the base, and has mounted thereon the sliding head K in the upper portion of which is the horizontally arranged slot L, which is adapted to 75 receive the key M which is composed of a flat bar having slits N in the edge thereof, either of which slits is adapted to engage the wall of the slot L when the key receives a quarter turn in said slot as most apparent 80 in Fig. 3, said key being adapted to enter either of the beds C and form a stop and gage for the coin placed in the bed so as to center the coin, support it in upright position and set it true in the wrapper when 85 occupying the bed.

It will be noticed that the head K may be 90 slidably moved on the bracket J so as to be placed in front of the bed relatively to the denomination of the coin to be wrapped, it being evident that the key M may be moved out or in relatively to the length of the roll of the coin, and so said roll whether of large or small coin, may be formed and centered 95 on the wrapper.

It will be seen that supposing that the bed on the left hand of Fig. 1, is adapted for silver dollars, the head K is moved to the center of said bed. Then a wrapper for such dollars is placed on the bed and an end thereof inserted under the adjacent bar G and so held down on the peak beneath said bar. The key M is now passed through the slot L to the extent required for a roll of silver dollars and turned so that the relative slit N engages with the wall of said slot and the key is interlocked with the head. The proper number of coins is now placed as a roll on the wrapper and sustained against the inner end of the key when it 105 will be centered or properly spaced on the wrapper. Then the wrapper is turned over 110

the roll while riding on the bed and the rollers E thereof. The end of the wrapper under the bar G slides out therefrom and overlaps the adjacent portion of the rolled 5 wrapper, when said end may be gummed and so closed. Of course, wrappers previously gummed may be employed, in which case the adhesive material or gum is moistened as usual. The key is then 10 turned and withdrawn and the coin as wrapped removed from the bed when the ends of the wrapper are folded in and closed as usual, thus completing the wrapping of the coin. The roll as formed may then be 15 stamped with the aggregate amount of the coin, unless the same has been printed on the wrapper.

It is evident that for wrapping coins of another denomination the head K is moved 20 to the proper bed when the key is applied and adjusted to the length of the roll of coin to be formed, the wrapper located in position on the bed and the coins piled on the wrapper one against the other until the 25 proper roll of coin is formed when the wrapping may be accomplished as heretofore.

Having thus described my invention what I claim as new and desire to secure by Letters Patent, is:—

1. In a coin wrapper, a bed having an elevated portion, a support therefor, rollers at the base of said bed, and a gravitating holder for a wrapper mounted on said elevated portion at the side of the roller and beneath which the wrapper is movable.

2. In a coin wrapper, a bed having an elevated portion, a support therefor, rollers at the base of said bed, a gravitating holder 40 for a wrapper mounted on said elevated portion at the side of the roller and beneath which the wrapper is movable, and a coin centering and sustaining member adjustable longitudinally and transversely of the bed 45 and adapted to enter the side of the bed.

3. In a coin wrapper, a series of beds, a support therefor, a gravitating wrapper holder between the beds, a member for centering and sustaining the coins in either of 50 said beds, and means for adjusting said member relative to the length of the roll of coins to be wrapped.

4. In a coin wrapper, a bed, a support therefor, a head mounted on said support, a 55 gravitating wrapper holder beneath which the wrapper may be moved, a coin-sustaining and centering member adjustable longitudinally and transversely of the bed and adapted to be fitted to said head and to enter 60 the side of said bed, and means for interlocking said member with said head in dif-

ferent position relatively to the length of the roll of coin to be wrapped.

5. In a coin wrapper, a bed, a support therefor, a head mounted on said support, 65 a gravitating wrapper holder beneath which the wrapper may be moved, said head having a slot therein, and a key adjustable longitudinally and transversely of the bed and adapted to be fitted in said slot and passed 70 into said bed at a side thereof, said key having means for interlocking it in different positions with said head.

6. In a coin wrapper, a series of beds, a support therefor, a sustaining and centering 75 key adapted to enter either bed at a side thereof, a head on which said key is adjustably sustained, and a carrier for said head, the latter being slidably mounted on said carrier, whereby said key is adapted to be 80 presented to the side of each bed of the series.

7. In a coin wrapper, a series of beds, a support therefor, a member for sustaining and centering the coin in either of said beds, 85 a device for carrying said member and means thereon for adjusting it relatively to the length of the roll of coin to be wrapped, and means for adapting said device for presentation of said member to the side of each 90 bed of the series.

8. In a coin wrapper, a series of beds, a support therefor, a bar extending lengthwise of said support and transversely of the length of the beds, a sliding member on said 95 bar, and a centering and supporting member adjustable in said bracket and adapted to be locked in position for use with either of said beds.

9. In a coin wrapper, a bed, a support 100 therefor, rollers at the base of said bed, a gravitating holder for a wrapper mounted on said support at the side of the roller and beneath which the wrapper is moved, and keepers for controlling the gravitating 105 holder against longitudinal movement when the wrapper rides thereunder in the direction of the bed.

10. In a coin wrapper, a bed, a support 110 therefor, rollers at the base of said bed, a gravitating holder for a wrapper mounted on said support at the side of the roller and beneath which the wrapper is moved, keepers for controlling the gravitating holder against longitudinal movement when the 115 wrapper rides thereunder in the direction of the bed, and a coin centering and sustaining member adapted to enter the side of the bed.
